DESIGN FOR A COMBINED ASH TRAY AND ARTICLE REST

Edward F. McDonald and Daniel L. Rumsey, Buffalo, N. Y., assignors to McDonald Products Corporation, Buffalo, N. Y.

Application May 16, 1941, Serial No. 100,989

Term of patent 7 years

To all whom it may concern:

Be it known that we, Edward F. McDonald and Daniel L. Rumsey, citizens of the United States, residing at Buffalo, in the county of Erie and State of New York, have jointly invented a new, original, and ornamental Design for a Combined Ash Tray and Article Rest, of which the following is a specification, reference being had to the accompanying drawing, forming part thereof.

Fig. 1 is a perspective view of the combined ash tray and article rest, showing our new design, and

Fig. 2 is a perspective view of the article rest looking at the opposite side from that shown in Fig. 1, the ash tray being omitted.

The characteristic feature of our design resides in the portion shown in solid lines.

We claim:

The ornamental design for a combined ash tray and article rest, as shown and described.

EDWARD F. McDONALD,
DANIEL L. RUMSEY.
